Primary Examiner — T Chase Nelson*Assistant Examiner* — Kelly L Gross(74) *Attorney, Agent, or Firm* — Bayramoglu Law Offices LLC(57) **CLAIM**

The ornamental design for a testing device, as shown and described.

DESCRIPTION

FIG. 1 is a front, right and top perspective view of a testing device showing our new design;

FIG. 2 is a rear, left and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a partially enlarged view showing the area “9” in FIG. 2;

FIG. 10 is a partially enlarged view showing the area “10” in FIG. 3; and,

FIG. 11 is a partially enlarged view showing the area “11” in FIG. 4.

The broken lines depict portions of the testing device that form no part of the claimed design. The dot-dash broken lines indicating an enlargement portion of the design form no part of the claimed design.

1 Claim, 11 Drawing Sheets(56)
